UNITED STATES PATENT OFFICE.

STONEWALL J. DOWLING, OF WAXAHACHIE, TEXAS.

VEHICLE-BODY CONSTRUCTION.

No. 809,788.

Specification of Letters Patent.

Patented Jan. 9, 1906.

Application filed July 8, 1905. Serial No. 268,767.

To all whom it may concern:

Be it known that I, STONEWALL J. DOWLING, a citizen of the United States of America, residing at Waxahachie, in the county of Ellis and State of Texas, have invented certain new and useful Improvements in Vehicle-Body Construction, of which the following is a specification.

This invention relates to new and useful improvements in buggy or vehicle bodies, and relates more particularly to the corner-irons employed in buggy or vehicle body construction.

It is an object of this invention to provide a device of this character that will form a compact and firm joint of a buggy or vehicle body and prove at the same time simple in construction and economical in manufacture.

With the foregoing and other objects in view the invention consists in the details of construction and in the arrangement and combination of parts to be hereinafter more fully described and claimed.

In describing the invention in detail reference will be had to the accompanying drawings, forming part of this specification, wherein like characters of reference denote corresponding parts in the several views, and in which—

Figure 1 is a view in perspective of the corner of a buggy or vehicle bed or body employing the invention. Fig. 2 is a view in perspective of the invention detached. Fig. 3 is a view in elevation of a fragment of a side strip or board, showing the manner in which it is cut when employed with a corner-iron constructed according to the invention.

In the drawings, 1 2 indicate the meeting base-beams of a buggy or vehicle body which have their meeting ends cut to form overlapping joints, as plainly indicated by dotted lines in Fig. 1. Suitably secured to the beams, preferably by bolts passing through apertures, is a corner-iron A. This iron extends above the beams a distance equal to the height of a buggy or vehicle body, as will be plainly understood by those familiar with buggy or vehicle body construction. The iron bar A is preferably L-shaped in cross-section and has formed on the inside at the junction of the members 4 5 a reinforcing-strip 6, which may be formed integral therewith or separate, according to the results desired in practice; but it is the intention of the invention to have the entire iron cast inte-

gral. The reinforcing-strip 6 is not of the same height as the iron proper, but extends from the upper edge of the iron down to a point slightly below the top or upper surface of the base-beam 1.

At the lower end of the strip 6 is a foot 7, which fits in a recess 8, formed in the beam 1. This foot projects on a line of about ninety degrees with relation to the members 4 5 of the iron A and is provided with an aperture 65 or opening 9, through which a bolt or other securing means is intended to pass in order that said foot may be attached to the beam 1. In practice it is the intention to have the bolt or whatever means is employed to pass through both of the beams 1 and 2. By this arrangement the foot not only provides a securing means for the angle-iron, but presents a means for holding the beams positively.

The inner surface of each of the members 4 5 of the iron A is reduced or recessed intermediate its width, said recess extending beyond the reinforcing-strip 6. From the top of each of the members 4 5 extends an arm 9^a, which is provided with a plurality of apertures through which screws or the like are intended to pass to engage the upper edge of the buggy or vehicle side strip B. The buggy or vehicle side strip B has its end portion 10 reduced in thickness to joint with the reduced portion of the members 4 5, while the upper and lower corners of the side are provided with cut-away portions 11 12, respectively, to receive the normal portions 13 of the members 4 5 and the arms 9^a of said angle or corner iron A. The reinforcing-strip 6 is also provided with a series of apertures extending therethrough to provide means whereby a dashboard may be applied. These apertures are preferably two in number and are located in those irons positioned at the front of the vehicle-body, as is thought to be understood by those skilled in the art.

The advantages of said invention and the operation thereof are thought to be clearly apparent from the drawings and the foregoing description thereof, it being stated that one of these irons is applied to each corner of a buggy or vehicle body.

Having fully described my invention, what I claim as new, and desire to secure by Letters Patent, is—

An angle-iron for a buggy or vehicle body comprising an L-shaped member, a rein-

force-strip arranged within the member at the junction of the sections, said member terminating at a point above the lower end of the member, a foot extending from the lower end of the member, arms extending from the upper edges of each of the sections of the members, the inner surfaces of each section being recessed intermediate its ends, said recess extending beyond the reinforce-strip;

said sections, arms and reinforce-strip being provided with apertures.

In testimony whereof I affix my signature, in the presence of two witnesses, this 1st day of July, 1905.

STONEWALL J. DOWLING.
